UNITED STATES PATENT OFFICE.

MANNIN GROSS, OF COUNCIL GROVE, KANSAS.

BURNER.

1,315,302.

Specification of Letters Patent.

Patented Sept. 9, 1919.

Application filed October 1, 1918. Serial No. 256,435.

To all whom it may concern:

Be it known that I, MANNIN GROSS, a citizen of the United States, residing at Council Grove, in the county of Morris and State of Kansas, have invented a new and useful Burner, of which the following is a specification.

The device forming the subject matter of this application is a vapor stove, and one object of the invention is to improve the burner, particularly, by providing a novel but simple means whereby superposed caps, which form a part of the burner, may be held in place removably. Another object of the invention is to provide a burner wherein carbon will not accumulate rapidly, it being possible to take down the burner readily for cleaning. A further object of the invention is to provide a device of the class mentioned, wherein the burner serves directly, as a means for holding in place, a sleeve carrying a deflector or a priming pan. It is within the province of the disclosure to improve generally and to enhance the utility of devices of that type to which the present invention appertains.

A mechanic may, within the scope of his skill, make changes in the device hereinafter described, within the purview of what is claimed, without departing from the spirit of the invention or jeopardizing the utility of the device forming the subject matter of this application.

The accompanying drawings, considered in connection with the description and the claims, disclose one of the many forms which my invention may take, and in the said drawings, Figure 1 is an elevation showing a vapor stove embodying the invention, parts being broken away; Fig. 2 is a section taken through the burner and attendant parts; Fig. 3 is a top plan of the burner, parts having been broken away.

In carrying out the invention, there may be provided a frame 1, constructed as desired. The frame 1, as shown, includes a ring 2 to which the upper ends of legs 3 are attached, the upper ends of the legs having sockets 4 wherein the lower ends of

standards 5 are mounted and secured. Adjacent to their upper ends, the standards 5 are offset, as shown at 6, and are inwardly extended, to form fingers 7. There may be any desired number of the standards 5, but three will form an adequate support for a spider 9, having open-bottomed U-shaped seats 8, wherein the fingers 7 are received.

The invention includes a receptacle 10 received removably in the ring 2 of the frame 1 and having an outstanding bead 11, which, coöperating with the ring, supports the receptacle. An air pump 12, of any desired kind, discharges into the receptacle 10, the valve mechanism of the air pump being indicated at 14. The receptacle 10 has a neck 15 through which oil or other liquid fuel may be introduced into the receptacle, the neck being closed by a screw cap 16 or other suitable closure. A tube 17 projects laterally from the neck 15 and communicates therewith, the tube having a side air vent 18 controlled by a valve 19 which may be threaded into the outer end of the tube.

The fuel passes upwardly from the receptacle 10 through a conduit including a pipe 20 threaded at 21 into the top of the receptacle and provided with a flange 22 engaging the top of the receptacle, the lower end of the pipe 20 being disposed relatively near to the bottom 23 of the receptacle, the bottom, if desired, sloping toward a central point beneath the pipe 20. The lower end of a nipple 24 is threaded at 25 into the upper end of the pipe 20, the nipple being surrounded by a sleeve 26, the lower end of which is supported by the flange 22. The sleeve 26 carries a deflector 27 serving to prevent the fuel receptacle 10 from being heated to an undesirable extent. A priming pan 28 is mounted on the sleeve 26 above the deflector 27 and may be supported thereby.

Referring to one of the important improvements in the device forming the subject matter of this application, attention is directed to a burner including a casing denoted generally by the numeral 30 and comprising a conical body 31 including a base 32 threaded at 33 on the upper end of the

nipple 24 and engaging the upper end of the sleeve 26. The sleeve thus is bound and held between the base 32 of the burner and the flange 22 of the pipe 20, no auxiliary nuts or like devices being required for holding the sleeve and, consequently, the deflector 27 and the priming pan 28, in place. A tip 34 is threaded at 35 into the base 32 and forms a termination of the conduit which includes the pipe 20 and the nipple 24. At its upper end, the body 31 of the burner is provided with a bowl 36 having an internal circumferential seat 38. There are elongated air inlet openings 37 in the body 31 below the bowl 36. The bowl 36 is provided with inwardly extended lugs 39 overhanging the seat 38.

The burner includes an inner inverted cup-shaped cap 40 having an outstanding flange 41 supported on and within the seat 38 beneath the lugs 39, the flange having a notch 42, adapted to receive one of the lugs, so that the cap can be removed at will from the bowl 36. The side wall of the inner cap 40 is imperforate, but there is an opening 43 in the top of the cap. The cap 40 is inclosed within an outer cap 44, the top of which is imperforate, the side wall of the cap 44 having relatively small perforations 45. The cap 44 is supplied with an outstanding flange 46, supported on the flange 41 of the inner cap 40 and extended beneath the lugs 39, the flange 46 having a notch 47, adapted to receive either of the lugs.

Especial attention is directed to the fact that the flanges 41 and 46 of the respective caps 40 and 44 may be placed beneath one of the lugs 39, the other lug passing through the notches 42 and 47 when the flanges are placed in the seat 38. By rotating the caps, the notches 42 and 47 may be moved from beneath either of the lugs, and thus both of the lugs, overhanging the flange 46 on the outer cap 44, will serve to hold both caps removably in place within the bowl 36. An accidental detachment of the caps 40 and 44 from the bowl 36, to the inconvenience of the operator, is not likely to occur. The burner, generally considered, is simple in construction, and devoid of places where carbon can collect. When the caps 40 and 44 are removed, the burner is open for cleaning, and it is to be observed that this opening of the burner may be brought about without difficulty.

When pressure is created within the receptacle 10 by the operation of the pump 12, the fluid fuel traverses the pipe 20, the nipple 24 and the tip 34, and mixes, within the body 31 of the burner, with air admitted through the openings 37, the inner cap 40 securing a thorough admixture of gas and air, before the mixture enters the outer cap 44 by way of the opening 43, the mixture

burning at the perforations 45 of the outer cap 44, the bowl 36 serving to direct the flame upwardly. At any time, the height of the flame may be decreased by retracting the valve 19, whereupon air will flow from the receptacle 10 by way of the vent 18, the tube 17 and the neck 15. When the vent 18 is closed by the valve 19, a stroke or two of the plunger of the pump 12 will restore or increase the pressure within the receptacle 10, and thus increase the flow of fuel through the pipe 20, raising the flame and increasing the heat.

When the device is first put into operation, it may be found desirable to place a small quantity of fluid fuel, such as wood alcohol or distillate, in the pan 28 and ignite the priming charge thus formed, in order to heat the burner and effect a vaporization of the fuel proceeding from the receptacle 10 through the tip 34.

The deflector 27, being interposed between the burner and the receptacle 10, prevents the possibility of an overheating of the receptacle and a consequent explosion.

Notches 100 may be formed in the upper edge of the bowl 36. These notches are adapted to receive a spanner wrench, used in threading the burner on the nipple 24, and in removing the burner therefrom. The notches, further, have another function, in that they aid in admitting air into the bowl 36, and promote combustion.

I claim:—

1. A burner comprising a body having a base, and provided at its upper end with a bowl, the body being supplied with an air inlet; inner and outer inverted cup-shaped caps supported in the bowl in spaced relation to each other, the outer cap being spaced from the inner surface of the bowl, the outer cap having side perforations, and the inner cap having an opening in its top, the interior of the inner cap being unencumbered, the inner cap communicating with the body throughout the entire cross section of the inner cap; and a tip carried by the base, the tip discharging directly into the inner cap.

2. A burner comprising a casing including a body having a base, and provided at its upper end with a bowl, the bowl being supplied with spaced overhanging lugs, the body having an opening; inner and outer inverted cup-shaped caps within the bowl, the caps having superposed flanges extended beneath the lugs and provided with notches for the reception of the lugs, the flange of the inner cap being supported on the bowl, and the outer cap having an imperforate top, and being supplied with side perforations, there being an opening in the top of the inner cap; and a tip carried by the base.

3. A burner comprising a bowl having an

internal shoulder; an inverted cup-shaped cap and a flange supported on the shoulder, and lugs on the bowl, the lugs overhanging the flange, the flange having a notch for the 5 passage of one lug.

In testimony that I claim the foregoing

as my own, I have hereto affixed my signature in the presence of two witnesses.

MANNIN GROSS.
